UNITED STATES PATENT OFFICE.

GUSTAVE BASTHEIM, OF PITTSBURGH, PENNSYLVANIA.

DESIGN FOR A WRIST-WATCH CASING.

Application filed February 16, 1922. Serial No. 735. Term of patent 3½ years.

To all whom it may concern:

Be it known that I, GUSTAVE BASTHEIM, a citizen of the United States, residing at Pittsburgh, in the county of Allegheny and State of Pennsylvania, have invented a new, original, and ornamental Design for Wrist-Watch Casings, of which the following is a specification, reference being had to the accompanying drawings, forming part thereof, in which:—

Figure 1 is a front elevation of the watch receiving case; and

Figure 2 is an edge elevation of the case shown in Figure 1.

I claim:

The ornamental design for a wrist watch casing, as shown.

In testimony whereof, I have hereunto set my hand.

GUSTAVE BASTHEIM.
